(57) **CLAIM**

The ornamental design for a water heater drip tray, as shown and described.

DESCRIPTION

FIG. 1 is a top perspective view of the water heater drip tray showing my new design;

FIG. 2 is a top view thereof;

FIG. 3 is a front view thereof;

FIG. 4 is a rear view thereof;

FIG. 5 is a bottom view thereof;

FIG. 6 is a right side view thereof, the left side view being a mirror image thereof;

FIG. 7 is a cross sectional view taken along line VII-VII of FIG. 2; and,

FIG. 8 is a cross sectional view taken along line VIII-VIII of FIG. 2.

The broken lines shown in the views depict environmental subject matter only and form no part of the claimed design.

1 Claim, 5 Drawing Sheets
